H. HACKENBURG.
PEPPER AND SALT SHAKER.
FILED JUNE 7, 1922.

Patented Mar. 27, 1923.

1,449,670

UNITED STATES PATENT OFFICE.

HERBERT HACKENBURG, OF WEEHAWKEN, NEW JERSEY.

PEPPER AND SALT SHAKER.

Application filed June 7, 1922. Serial No. 566,622.

To all whom it may concern:

Be it known that I, HERBERT HACKENBURG, a citizen of the United States, and a resident of Weehawken, county of Hudson, and 5 State of New Jersey, have invented certain new and useful Improvements in Pepper and Salt Shakers, of which the following is a specification.

The present invention relates to improvements in pepper and salt shakers in which a single article of table ware is made to contain separate compartments for these two condiments, an object of the invention being to provide for a simplified control of the 10 perforated top of the receptacle to enable the release of either the pepper or the salt while confining the other condiment in its respective compartment.

Other objects of the invention are to improve 15 the bottom construction of the receptacle whereby it may be quickly and conveniently removed to permit of replenishing the compartments with the salt and pepper or other condiments; to provide for an effective locking of the removable bottom in 20 place, and to so arrange and coordinate the parts as to permit of the control for the exit of the condiments by means of a shifting movement of the bottom, which renders 25 its action exceedingly convenient and positive.

Further objects of the invention are to render the entire construction simple and inexpensive to make, to enable the easy filling 30 of the compartments with the condiments and to keep the salt and pepper at all times apart both in the receptacle and in the delivery thereof.

With the foregoing and other objects in 35 view, the invention will be more fully described hereinafter, and will be more particularly pointed out in the claims appended hereto.

In the drawings, wherein like symbols 40 refer to like or corresponding parts throughout the several views.

Fig. 1 is a side view of a shaker constructed according to the present invention.

Fig. 2 is a top plan view thereof.

Fig. 3 is a vertical section taken centrally through the device.

Fig. 4 is a bottom plan view of the receptacle showing a slight modification.

Fig. 5 is an interior plan view of the modified bottom used in connection with device illustrated in Fig. 4.

Fig. 6 is a fragmentary sectional view showing these parts interlocked.

Fig. 7 is a fragmentary perspective view showing the bottom construction on an enlarged scale.

Fig. 8 is a fragmentary enlarged section showing the same construction.

Fig. 9 is a fragmentary side view of the receptacle with the bottom detached and showing a further modification.

Fig. 10 is a cross section through the particular bottom used in this case.

Fig. 11 is a cross section of a modified form of device, whereby the central portion 70 may be filled from the exterior, by simply removing a cap.

Fig. 12 is a plan view of the modification shown by Fig. 11.

Referring more particularly to the drawings 75 1 designates the receptacle or casing made from sheet metal or other appropriate material and preferably being frusto-conical with the top 2 closed except that perforations 3 are provided therein and similar perforations 4 in the raised central portion or boss 5 of said top. The perforations 3 are closed by an annular plate 6 also having ports 7 to register with the perforations 3 upon the angular adjustment of the plate. 80 This ported plate 6 is carried by a tube or barrel 8 extending axially through the receptacle and constituting a chamber or compartment separate and distinct from that below the perforations 3. The annular compartment 9 may contain, for instance salt, while the central compartment 10 receives pepper; although it is to be understood that other condiments may be placed therein.

The barrel or tube 8 is of a size to fit at 95 its closed end into the boss 5 which gives it the proper bearing for holding the same in place, while permitting of its rotation to enable the perforations 11 in the barrel's closed top to align with the perforations 4. 100 It will be noted from Fig. 3 that when registry is had between the perforations 4 and 11, the salt compartment 9 will be closed by reason of the non-alinement of the perforations 3 and 7. Conversely, when the perforations of the salt compartment are brought, by angular adjustment of the barrel and plate 6, into alinement, there will be no registry of the central perforations.

The lower edge of the receptacle 1 is, according to one form of the invention, adapted to receive therein a metallic or other sleeve

12 having an intermediate pressed-out bead 13 engaging the lower part of the receptacle and forming a stop for the flange 14 of the bottom 15. The construction is such that a 5 resilient frictional action is had between the lower projecting part of the sleeve 12 and the flange 14 in order to hold the bottom in place and in the adjusted angular position. The bottom 15 closes both compartments 9 10 and 10 but the central compartment 10 is preferably also independently closed by the use of a cork or other stopper 16 having a pull cord 17 if desired. This independent stopper prevents the salt from the outer 15 compartment getting into the central compartment upon inverting the receptacle, as when taking off the bottom 15.

The salt is apt to get from the outer compartment upon the bottom of the cork or 20 stopper 16 through the inverted V-shaped incisions or slots 18 made in the lower edge of the barrel 8 to receive a correspondingly formed projection or rib 19 extending diametrically across the central part of the 25 bottom 15. This construction provides an interlock for rotating the barrel 8 upon rotation of the bottom 15, which is facilitated by milling or corrugating the flange 14 to permit a more positive grasp in the fingers.

30 A stop-finger 20 projects upwardly upon the exterior of the flange 14 and is disposed to encounter a pair of lugs 21 and 22 situated upon the outside surface of the bottom portion of the receptacle 1.

35 In the operation of the device, the receptacle is inverted and the bottom 15 lifted off whereupon salt for instance is loaded into the annular compartment 9. The stopper 16 being drawn out, pepper or other suitable 40 material may be placed in desired quantities in the central compartment 10. The stopper 16 and bottom 15 are thereupon replaced and the receptacle righted. When pepper is desired for instance, the bottom 15 45 is turned so that the finger 20 engages the stop lug 21. In this position the perforations 4 and 11 register and pepper may be freely shaken out of the central compartment 10, while the plate 6 masks the perforations 3 to avoid the simultaneous escape 50 of the salt. Upon rotation of the bottom 15 so that the finger engages the opposite stop lug 22, a closing of the central perforations 4 and 11 and an opening of the perforations 3 and 7 55 will be effected to permit of the shaking of the salt upon the food.

60 Referring now to Figs. 4 to 8, inclusive, a slightly different form of fastening for the bottom 15 is provided, which includes the continuation of the side wall of the receptacle downwardly and outwardly in a substantially horizontal direction to provide a shoulder 23. This shoulder lies above a second similar shoulder 24 preferably made 65 in the same piece of sheet metal and con-

nected by folding at its outer edge with the upper shoulder 23. A further return of the metal upon itself is made to provide a flange 25 placed below the intermediate shoulder 24. In other words, as indicated in Fig. 8, 70 the metal takes the form of an S. As represented in Fig. 4, portions of the flange 25 are cut away, as indicated at 26 and 27, to receive the flanges 28 and 29 of the bottom 15 shown in Fig. 5. After flanges 28 and 29 75 are inserted in the slots 26 and 27, the bottom 15 is given a quarter turn, thus bringing the flanges 28 and 29 into interlocking engagement with opposite unslotted portions of the receptacle flange 25. The interlocking engagement is shown in Fig. 6. The flange 29 of the bottom is shown in Fig. 5 to be provided with a cut-out portion 30 which also appears in Fig. 8 and this is occupied by a pressed-up spring bead 31 on the flange 25 85 of the receptacle. The bottom flange 29 is also provided with a sloping upper-surface 32 to take against the intermediate shoulder 24 whereby to pry these spring metal elements apart to form a tight binding 90 engagement of the receptacle flanges with the bottom 15 to avoid the loss of the salt or other material in the outer compartment 9.

According to this form of the invention 95 the bottom is connected with the receptacle by securing registry of the bottom flanges 28 and 29, with the slots 26 and 27, the bottom being then forced down upon the inverted receptacle until the flanges 28 and 29 are in position upon rotation to engage 100 beneath the unslotted portions of the receptacle flange 25. Upon turning the bottom or the receptacle a quarter of a revolution, the flanges will be interlocked and inasmuch as the spring bead 31 snaps into the cut-away 105 portion 30, casual rotation and disengagement of the bottom will be positively avoided. This form of the invention will be found to allow of a quick detachment and replacement of the bottom and in this way 110 will facilitate the replenishing of the compartments, while at the same time forming a very effective barrier to the escape of the contents.

115 In connection with Figs. 9 and 10, there is shown a still further modified form in which the receptacle is provided with a flange 33 which is set in from the plane of the side wall and has diametrically disposed bayonet slots 34 and 35 made therein to receive the pins 36 and 37 upon the flange 38 of the bottom 15. In this instance, as also 120 in Fig. 6, the rib which locks the bottom with the barrel 8 is square in cross section as indicated at 39 instead of being V shape 125 as in Fig. 3. It will be understood that the form of this rib may be varied as desired, it being only necessary that a positive locking engagement result from the interfitting of these parts.

The bottom 15 shown in Fig. 10 is fitted with the flange 38 lying outwardly of the receptacle flange 33, care being taken to bring the pins 36 and 37 into a correct position to enter the bayonet-slots 34 and 35. The pins are pressed inwardly and the bottom 15 rotated to cause the pins to enter the diagonal portions of the slots and to lock the bottom tightly in place. It will be seen

10 that the diagonal portions of the bayonet slots are elongated to permit of a fractional revolution of the bottom when opening and closing the ports of the pepper and salt compartment.

15 In Figs. 11 and 12 a modified form is shown whereby the cover of the central portion may be removed and pepper filled into the central portion after the cap is removed.

It will be appreciated from the foregoing 20 that the present invention provides a compact bottom construction for receptacles of this character in which the filling of the receptacle is had through the wider bottom portion, rendering the operation easier and 25 which bottom portion also provides for the control of the two compartments. The construction thus simplifies the top of the receptacle and avoids the clogging of the operating parts or deterioration through the action of the salt.

30 I have illustrated and described preferred and satisfactory embodiments of my invention, but it is obvious that changes may be made therein within the spirit and scope 35 thereof as defined in the appended claims.

What is claimed is:

1. A salt and pepper shaker comprising a receptacle having separate compartments therein for the salt and pepper with individual outlets therefor at the top of the receptacle, means to open and close the outlets, and a removable bottom for filling both compartments and being connected with said means whereby to open or close the outlets upon a shifting movement of the bottom.

2. A condiment holder comprising a receptacle having separate and distinct compartments therein with independent outlets 50 at the upper portion of the receptacle, means to control the opening and closing of the outlets and arranged to open one outlet

while closing the other, and a detachable bottom for the receptacle giving access to both compartments and having a rotary 55 movement on the receptacle, said bottom being connected to said control means for the outlets whereby upon rotation of the bottom to cause selective opening and closing of the compartments.

3. A receptacle having separated compartments for two different condiments or the like provided with a closed top with two sets of sifting perforations in communication with the compartments, means 65 to control the opening and closing of the compartment perforations, a rotary detachable bottom on the receptacle connected to operate said control means, and stop means for the bottom.

4. A receptacle provided with compartments having outlets, means to control the outlets acting alternately, a rotary detachable bottom for the receptacle having connection to said means, and means to hold 75 the bottom detachably and for partial rotation upon the receptacle.

5. A receptacle having a closed top with an outwardly offset central portion, the top and offset portion being provided with 80 perforations, a tube fitted in the receptacle and mounted for turning at its inner end in the offset portion, said tube having perforations to agree with the perforations in the offset portion, a ported plate carried by the 85 tube to open and close the perforations in the top, and a bottom detachably held upon the receptacle and having an interlocking engagement with the tube.

6. A receptacle having compartments 90 with outlets leading therefrom, a control means for the outlets, a detachable bottom for giving access to said compartments and means to independently close one compartment at the bottom, said receptacle and detachable bottom having means acting on rotation to interlock the bottom with the receptacle, said detachable bottom having a detachable interlocking connection with said control means.

In testimony that I claim the foregoing as my invention, I have signed my name hereunder.

HERBERT HACKENBURG.
